Primary Examiner—M. H. Tung*Attorney, Agent, or Firm*—Larry M. Jennings[57] **CLAIM**

The ornamental design for a tree waterer, as shown and described.

DESCRIPTION

FIG. 1 is a top perspective view of a tree waterer showing my new design, on an enlarged scale, the drawing of a portion of a tree is for illustrative purposes only and forms no part of the claimed design;

FIG. 2 is a top plan view thereof;

FIG. 3 is a bottom plan view thereof;

FIG. 4 is a left side elevational view thereof, the right side being a mirror image of the left side shown;

FIG. 5 is a front elevational view thereof; and,

FIG. 6 is a back elevational view thereof.

The broken line drawing of a tree in FIG. 1 is for illustrative purposes only and forms no part of the claimed design.
